INC., OF SYRACUSE, NEW YORK, A CORPORATION OF NEW YORK

SPRING PAD CONSTRUCTION

Application filed January 2, 1930. Serial No. 417,902.

This invention relates to spring pads for pressing machines and has for its object a spring pad which is particularly simple and economical in construction and highly efficient and durable in use.

The invention consists in the novel features and in the combinations and constructions hereinafter set forth and claimed.

In describing this invention, reference is had to the accompanying drawing in which like characters designate corresponding parts in all the views.

Figure 1 is an elevation, partly in section, of this spring pad, showing the same applied to the pressing element or the buck of a pressing machine.

Figure 2 is an enlarged fragmentary sectional view of the spring padding.

Figure 3 is a side elevation of a pressing machine showing one location of the pad.

This pad comprises generally, a base sheet of padding material and a spring backing therefor interposed between the base sheet and the pressing element or other support, the spring backing including a plurality of springs distributed over the area of the inner or under side of the padding sheet, the springs having like ends embedded or interlocked in the base padding sheet, the ends of the springs which rest on the buck or other support being preferably free or disconnected from each other.

1 designates the base sheet of padding material, this being preferably made of mineral or steel wool, in any well known manner.

2 are the coiled springs constituting the support or backing for the sheet 1, the end coils of the springs being embedded in the sheet 1 as by screwing or turning them into the sheet and the extreme ends of the coils are formed annular or with hooks 3 which interlock in the base sheet to prevent dislodgement of the springs. The pad is arranged with the base sheet outwardly and with the outer or free ends of the springs 2 on the supporting surface, as the face of the buck 4, of a pressing machine.

The padding is usually overlaid with an outer cloth wrapper 5 secured at its margin in any suitable manner to the buck 4. The

padding may be applied to either the upper or lower pressing element of a pressing machine, and in the machine shown in Figure 3, it is shown as applied to the lower pressing element or buck 4, which is mounted on a suitable frame 6. The upper pressing element or head 7 is movable into and out of pressing position by any well known actuating mechanism.

This pad is advantageous in that it is not only simple and economical in construction because the springs are supported directly in the base sheet 1 without special fastening means, but also because the base sheet being interwoven metal fibres or steel wool forms a particularly good base to which to attach the springs. The padding thus constructed consists of but two elements, the base sheet and the springs.

What I claim is:

1. A spring pad for pressing machines comprising a base sheet of padding material and a spring backing for said base sheet consisting of a plurality of springs having their ends interlocked in the base sheet and terminating short of the face of the base sheet.

2. A spring pad for pressing machines comprising a base sheet of padding material and a spring backing behind said base sheet consisting of a plurality of coiled springs having their coils at like ends embedded in the padding of the base sheet, the greater portion of the coil springs extending outside of the base sheet.

3. A spring pad for pressing machines comprising a base sheet of mineral wool padding and a plurality of springs for supporting the base sheet and located in position to form a backing therefor, said springs having their ends embedded in the base sheet and terminating short of the face of the base sheet.

4. A spring pad for pressing machines comprising a base sheet of mineral wool padding and a plurality of springs for supporting the base sheet and located behind the base sheet to form a backing therefor, said springs being coiled springs and having like ends embedded in the base sheet and terminating short of the face of the base sheet.

5. A pressing jaw, for a garment or laundry pressing machine, including a supporting member formed with a face; a plurality of coil springs mounted on the face with their lower ends resting on the face; a pad filled with steel wool and supported by the coil springs; a cover overlying the pad and secured to the supporting member; the upper end portions of the coil springs extending into and terminating in the lower part of the pad short of the cover overlying the pad.
